US0D1095018S

(12) **United States Design Patent** (10) **Patent No.:** **US D1,095,018 S**
(45) **Date of Patent:** **** Sep. 30, 2025**

(54) **MAGNETIC CARD SLEEVE**

(71) Applicant: **Electronic Silk Road (Shenzhen) Tech Co., Ltd.**, Guangdong (CN)

(72) Inventor: **Jiahui Hong**, Guangdong (CN)

(73) Assignee: **Electronic Silk Road (Shenzhen) Tech Co., Ltd.**, Shenzhen (CN)

(**) Term: **15 Years**

(21) Appl. No.: **29/939,387**

(22) Filed: **Apr. 26, 2024**

Related U.S. Application Data

(63) Continuation-in-part of application No. 35/516,817, filed on Mar. 10, 2023 (U.S. filing date under 35 U.S.C. 384), and having an international filing date of Mar. 10, 2023, now abandoned.

(30) **Foreign Application Priority Data**

Nov. 11, 2022 (CN) 202230753805.9

(51) **LOC (15) Cl.** **03-01**

(52) **U.S. Cl.**

USPC **D3/247**

CLAIM

The ornamental design for a magnetic card sleeve as shown and described.

DESCRIPTION

FIG. 1 is a top, front and left side perspective view of a magnetic card sleeve showing my new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a rear and right side perspective view showing the magnetic card sleeve in a first open state;

FIG. 10 is a rear elevational view of the magnetic card sleeve in a second open state;

FIG. 11 is a front elevational view of the magnetic card sleeve in the second open state; and,

FIG. 12 is a left side view of the magnetic card sleeve in the second open state.

The evenly dashed broken lines in the drawings illustrate portions of the magnetic card sleeve which form no part of the claimed design.
